UNITED STATES PATENT OFFICE.

REBECCA JANE JACOBUS, OF OAKLAND, CALIFORNIA.

ABSORBENT COWL FOR THE CHIMNEYS OF HYDROCARBON-BURNERS.

SPECIFICATION forming part of Letters Patent No. 326,565, dated September 22, 1885.
Application filed May 26, 1884. (No model.)

To all whom it may concern:

Be it known that I, REBECCA JANE JACOBUS, a citizen of the United States, residing at Oakland, in the county of Alameda and State 5 of California, have invented or discovered a new and useful Absorbent Cowl for the Chimneys of Hydrocarbon-Burners, such as Stoves, Lamps, &c., of which the following is a specification.

10 My invention or discovery consists in providing a hood or cowl made of plaster-of-paris or other solid or porous substance capable of absorbing gases, which has indentations on its inner face, and is provided with 15 one or more internal perforated plates and which is placed over the draft-hole or chimney of hydrocarbon-burning vessels, such as stoves, lamps, &c., to receive and absorb the smoke and gases or waste products of combustion that are unconsumed.

15 The accompanying drawing, forming a part of this specification, represents a central vertical section taken through my improved smoke-absorbing hood or cowl for hydrocarbon-burning vessels.

20 A represents a hood or cover, which is cast or molded of ground gypsum, plaster-of-paris, or other mineral, earthy, or porous substance capable of absorbing smoke and gases; 25 but I prefer plaster-of-paris, as this mineral is comparatively cheap and easy to operate with. The cover is supported upon the sides of the stove or chimney of the vessel or burner by means of feet or lugs B, while the lower rim 30 or edge of the cover extends downward a little below the top of the stove or chimney A', so as to admit atmospheric air and permit it to pass freely up into the cover.

35 For lamp-chimneys a supporting-rim may be connected to the chimney or lamp capable of sustaining the weight of the cover, lid, or hood.

40 The top of the cover is provided with a dome or knob, C, as shown, useful for the purpose of lifting the cover and removing it 45 from the vessel when desired.

45 The inner face of the hood or cover is thickly penetrated with conical or funnel shaped holes D, of about the size of an ordinary nail-head at the initial point, and these holes are 50 made as closely together as possible yet so as

not to interfere with each other, and they extend only about half way through the cover.

Inwardly-projecting rims or lugs E E are cast upon the interior surface of the cover to 55 receive and support two perforated absorbing shelves or plates, F and G. These plates are made of plaster-of-paris, and the upper one, or that designated by the letter F, is cast about an inch and one-half in thickness while 60 the lower one, G, need not be made so thick. The lower faces of both these plates are pierced with funnel-shaped or tapering holes in a similar manner to those described in the inner face of the cover or hood, which holes pass 65 through the upper faces of both plates. The holes in the upper face of the lower plate are, however, made a little larger than those in the upper face of the upper plate—say about the size or diameter of that made by an ordinary 70 pin—while those which terminate in the upper face of the upper plate are scarcely perceptible, the object being to permit as much of the waste products of combustion as the lower plate will readily absorb to enter it, and 75 the surplus or residue to pass up by draft or suction through the pin-holes of this lower plate and on and into the upper plate, and any surplus that is not absorbed by the upper plate will still pass through the smaller 80 perforations contained in the upper plate into the body of the hood where it is entirely absorbed.

85 Care should be taken, however, not to pierce the holes entirely through the cover or hood, as it is intended that these holes shall be only half-way through this cover. No indication of these holes should be seen on the outer surface thereof. Thus it will be seen that as no outlet is made in the cover or hood 90 the lesser products of combustion remaining will be absorbed by the cover after passing through the plates beneath, and no trace of either smoke or gas remains to escape into the apartment.

95 Should the absorbing plates and hood become fouled or clogged by constant use, they may be immersed in water at the ordinary temperature for a few minutes, when they will be renewed and ready for use again.

100 I am aware that a gas-stove has been provided with a perforated cover composed of a

porous refractory material, such as terra-cotta or fire-clay, the perforations in said cover being proportioned in size and number to the capacity of the gas burner or burners, so that the products of combustion will be retained in the stove and consumed without vitiating the air. This, however, I do not claim. My absorbent cowl being formed with indentations on its inner face and provided with ²⁰ movable internal perforated plates, as described, presents an extended surface for the complete absorption of the smoke and unconsumed gases of a hydrocarbon - burner. It will also be observed that the construction of ²⁵ the cowl is such that it can be readily cleansed when required.

Having thus described my invention, what I claim, and desire to secure by Letters Patent, is—

An absorbent cowl for hydrocarbon-burners, ²⁰ consisting of a hood formed of absorbent material and having indentations on its inner face, said hood being provided with one or more internal perforated absorbent plates, substantially as described. ²⁵

In testimony that I claim the foregoing I have hereunto set my hand and seal.

REBECCA J. JACOBUS. [L. s.]
